LIGHTER

George Philip Schmitt, New York, N. Y., assignor
to Cardinal Products, Inc., a corporation of
New York

Application September 12, 1933, Serial No. 689,114

10 Claims. (Cl. 67—7)

This invention relates to catalytic lighters for cigarettes and the like, wherein vaporizable fluid carried by absorbent material is caused to co-act with a catalytic element in the presence of air, to thus render such catalytic element incandescent, so that a cigarette or the like applied thereto and drawn upon, may be ignited.

Lighters of this character, exemplified in U. S. Patent No. 1,899,008, dated February 28, 1933, 10 provide a spacing chamber between the absorbent and the catalyst, with air admission means to the chamber, but this arrangement which is effective for a period when the absorbent material is freshly charged with vaporizable fluid, fails to function satisfactorily after that period, although the absorbent material may still contain a quantity of fluid, because suction applied through the cigarette will not draw the fluid from more remote portions of the absorbent material.

20 Therefore my invention consists in the provision of means, employed in a lighter of this character, for conducting atmospheric air to the base of the absorbent material, together with the provision of a passageway through the absorption material, so that suction applied to the outer end of the absorbent material will induce a flow of air to pass entirely through the absorbent material, thereby serving to convey to the catalyst the fuel which is picked up in transit.

30 Other features and advantages of my invention will hereinafter appear.

In the drawing:—

Figure 1 is a side sectional view of my improved lighter.

35 Fig. 2 is a section on the line 2—2 of Fig. 1. Fig. 3 is a section on the line 3—3 of Fig. 1. Fig. 4 is a perspective view, exploded, and partly broken away, of the container of the absorbent material and the holder for the catalyst, and 40 Fig. 5 is a side elevation of the lighter, showing the closure cap fitted thereon, in section.

In said views let 1 indicate the lighter casing, having a cap 2 to fit removably thereover, and let 3 indicate a cylindrical sleeve which is adapted 45 to contain absorbent material, such for example as cotton wool, here indicated at 4. The casing is provided with an annular shoulder 5, to form a seating stop for the cap.

A hollow, cylindrical holder 6 is adapted at 50 one end to fit snugly, but removably, over the outer end of sleeve 3, said outer end being reduced in diameter, as at 7, to receive said holder, in order that the sleeve and holder, when fitted together, may have the same outside diameter throughout their combined length. This is for

the purpose of enabling the united sleeve and holder to fit tightly, though removably, within the casing. The holder 6 has an inturned flange 8 at its outer end, to retain the catalytic element, which appears here in the form of a block or pellet 9 of spongy platinum composition, having an aperture 10 therethrough. The pellet 9 is supported in a socket 11, having an apertured base and a surrounding wall 12, said socket, like the pellet 9, being retained by the inturned flange 8.

As means for localizing the socket and pellet I employ a split ring 13 which is tensioned within the holder and lies against the socket.

The socket 11 is made of magnesium composition or other suitable material that is non-absorbent and is of a refractory nature.

The absorbent material 4 is held within sleeve 3 at its lower end as by lugs 14, cut from said sleeve and inturned to thus support the absorbent material spaced from the bottom of casing 1, to provide a clearance 15. A perforated tube 16, (see Fig. 4) or a wire helix 17, having spaced coils, to thus form a tube, is disposed axially of the sleeve 3, being embedded in the absorbent material, one end of said tube, 16 or 17, opening into clearance 15, and its other end opening into a space or chamber 18 that is formed in the holder 6, between socket 11 and the absorbent material.

In order that heat from the pellet 9 may not char the absorbent material 4, I place upon its upper end a block 19 of heat resisting, fluid permeable material, having an orifice 20 that is aligned with the end of tube 16 or 17, said block 35 19 forming a cap for the absorbent material 4 and being localized as such by means of a flange 21 that is inturned from the upper end of sleeve 3.

The sleeve 3 is provided with one or more longitudinal, indented channels 22 which communicate at their lower ends, through the gaps 23 formed in cutting out lugs 14, with the clearance 15. Similar channels 24 are formed in holder 6, the channels 22, 24 interfitting to form one continuous channel when the holder is fitted upon 45 the sleeve.

The upper end of this continuous channel, indicated at 25 in Fig. 5, is exposed to the atmosphere when the cap 2 has been removed, whereby, upon applying suction to pellet 9, as by drawing upon a cigarette whose end is placed over aperture 10, atmospheric air is induced to flow through channels 24, 22, clearance 15, and up through tube 16 or 17, in which latter path the air picks up fuel from absorbent material 4 and 50 55

causes the mixture of air and fuel to impinge upon pellet 9, with the resulting incandescence of the latter, which ignites the cigarette.

It being desirable that the act of removing cap 2 shall have the effect of inducing a flow of atmospheric air to pass through channels 24, 22, clearance 15 and tube 16 or 17, therefore I provide an annular bead 26 on casing 1, which bead is to be snugly engaged by cap 2, to create an air-tight closure, whereby the act of removing the cap serves in the manner of a vacuum pump to draw a charge of fuel and air up against the pellet. Also this air-tight closure means prevents evaporation of the fuel.

15 The casing 1 is also provided with a bayonet slot 27, and the holder 6 bears a protuberance 28 that is adapted to engage said slot to localize the holder, with the connected sleeve 3, and to lock them in the operative position.

20 Variations within the spirit and scope of my invention are equally comprehended by the foregoing disclosure.

I claim:-

1. A lighter comprising a casing, a sleeve removably fitting said casing, absorbent material, to be saturated with vaporizable fuel, contained within said sleeve, a hollow holder axially and removably engaging said sleeve, a catalytic element carried by said holder in spaced relation with the absorbent material in said sleeve, and admission means enabling a flow of atmospheric air to pass lengthwise entirely through said absorbent material, toward the catalytic element, to convey fuel thereto.

25 2. A lighter comprising a casing, a sleeve removably fitting said casing, absorbent material, to be saturated with vaporizable fuel, contained within said sleeve, a perforated, tubular member embedded lengthwise within said absorbent material, a hollow holder axially and removably engaging the outer end of said sleeve, a catalytic element carried by said holder, in spaced relation with the absorbent material in said sleeve, and admission means enabling a flow of atmospheric air to pass lengthwise through said tubular member toward said holder, to entrain fuel and convey it to said catalytic element.

30 3. A lighter comprising a casing, a sleeve removably fitting said casing, absorbent material, to be saturated with vaporizable fuel, contained within said sleeve, a hollow holder removably engaging said sleeve, a catalytic element carried by said holder in spaced relation with the absorbent material in said sleeve, said sleeve and holder being indented longitudinally and coincidentally, and said sleeve being ported near its base, to co-act with said casing in providing a passageway leading to the base of the absorbent material, whereby a suction pull through the holder will create a flow of atmospheric air through the absorbent material to entrain fuel and convey it toward the catalytic element.

35 4. A lighter comprising a casing, a sleeve removably fitting said casing, absorbent material, to be saturated with vaporizable fuel, contained within said sleeve, a perforated, tubular member embedded lengthwise within said absorbent material, a hollow holder removably engaging said sleeve, a catalytic element carried by said holder, in spaced relation with the absorbent material in said sleeve, said sleeve and holder being indented longitudinally and coincidentally, and said sleeve being ported near its base, to co-act with said casing in providing a passageway leading to the base of said tubular member, whereby

a suction pull through the holder will create a flow of atmospheric air through said tubular member, to entrain fuel from the absorbent material and convey it toward the catalytic element, the indenting in the holder extending above the casing wall, and removable closure means for said casing adapted to cover said holder and admission means.

5 5. A lighter comprising a casing, a sleeve removably fitting said casing, absorbent material, to be saturated with vaporizable fuel, contained within said sleeve, a hollow holder axially and removably engaging said sleeve, a socket composed of refractory material supported by said holder, a catalytic element carried by said socket in spaced relation with the absorbent material in said sleeve, and admission means enabling a flow of atmospheric air to pass lengthwise entirely through said absorbent material, toward the catalytic element, to convey fuel thereto.

10 6. A lighter comprising a casing, a sleeve removably fitting said casing, absorbent material, to be saturated with vaporizable fuel, contained within said sleeve, an apertured cap composed of permeable, heat resisting material fitted in said sleeve at its upper end to form a retaining top for the absorbent material, a hollow holder removably engaging said sleeve, a catalytic element carried by said holder in spaced relation with said cap, and admission means enabling a flow of atmospheric air to pass lengthwise entirely through said absorbent material, toward the catalytic element, to convey fuel thereto.

15 7. A lighter comprising a casing, a sleeve removably fitting said casing, absorbent material, to be saturated with vaporizable fuel, contained within said sleeve, a hollow holder removably engaging said sleeve, a catalytic element carried by said holder in spaced relation with said absorbent material, means for the admission of air to the base of said absorbent material, an annular bead on said casing, and removable closure means for said casing adapted to cover said holder and admission means, and to co-act with said bead in creating an air-tight enclosure whereby, in removing the closure means a vacuum pumping effect is produced serving to pass air through the absorbent material in the path to the catalytic element.

20 8. A cigarette lighter comprising an open ended casing, an absorbent material adapted to be charged with vaporizable fluid disposed within said casing, a cap fitted over one end of said casing, a disk of catalytic material supported by said cap in the path of vapor from said fluid, a surface of said disk being disposed for contact with a cigarette or the like, said casing being provided with means for the admission of air to the underside of said casing, and an air and vapor mixing chamber extending through said casing, whereby a supply of fumes will be presented to the underside of said disk.

25 9. A lighter comprising an open ended casing, an absorbent material adapted to be charged with vaporizable fuel disposed within said casing, a disk of catalytic material supported co-axially on the open end of said casing in the path of vapor from said fuel, a surface of said disk being disposed for contact with a cigarette or the like, said casing being provided with a passage for the admission of air to the underside of said casing, and a passageway through said absorbent material communicating at the lower end with the interior of said casing and the air inlet passage and opening at the other end adjacent said

catalytic material to deliver a supply of air and vapor mixture thereto.

10. A lighter comprising a casing, a wick disposed in the casing and adapted to hold a quantity of volatile liquid, a cover movable into and out of engagement with the casing, a support carried by the casing above said wick, a catalytic

element mounted on said support, said cover being arranged to uncover an air port to permit the flow of air to the wick, the wick having a passage therein to receive the air, said passage being arranged to emit air carrying vapor from the wick to the catalytic element.
